CHRISTMAS TREE

Percy Dieffenbach, R.F.D. 1, Olyphant, Pa.

Filed June 17, 1963, Ser. No. 75,380

Term of patent 14 years

(Cl. D29—1)

The figure on the drawing is a front view of a Christmas tree showing my new design. The back of the tree is undisclosed in the drawing but presents a substantially similar appearance as the front.

I claim:

The ornamental design for a Christmas tree, as shown and described.
